UNITED STATES PATENT OFFICE.

GEORGE W. ACKERMAN, OF NEW YORK, N. Y., ASSIGNOR TO ACKERMAN DOOR INTERVIEWER CORP., OF NEW YORK, N. Y., A CORPORATION OF NEW YORK.

GRILLE.

Application filed July 20, 1926. Serial No. 126,055.

An object of the present invention is to provide a grille capable of a wide range of utility, but which finds its preferred embodiment in a device for use on apartment doors.

An object of the invention is to provide a device of this character which will permit the occupant of an apartment to observe applicants for entrance without opening the door, to pay bills, or carry on conversation through the grille without any danger of an intruder gaining entrance or inserting his hand through the grille to open the door from the inside.

In its preferred embodiment the grille includes a pair of frame members of similar size and shape, the outer frame member carrying a grating or a plurality of bars for restricting the size of the opening, and the inner frame member carrying a closure for closing the opening.

Preferably the two frame members, one at the outside and one at the inside of the door are held together by securing devices which are inaccessible from the outside of the door, so that there is no danger of an intruder prying off, or forcibly dislodging the grille from its position in the door.

Other objects of the invention are to provide a grille of simple, practical construction which will be neat and attractive in appearance, rugged, durable and efficient in use, and well suited to the requirements of economical manufacture.

With the above noted and other objects in view, the invention consists in certain novel features of construction and combinations and arrangements of parts, as will be more fully hereinafter set forth and pointed out in the claim. The invention may be more fully understood from the following description in connection with the accompanying drawings, wherein—

Fig. 1 is a view in inside elevation of an apartment door showing my improved grille in applied position.

Fig. 2 is an enlarged elevational view of the inside of the grille showing the closure plate closed and latched.

Fig. 3 is a similar view looking at the outside of the grille.

Fig. 4 is a transverse sectional view on the line 4—4 of Fig. 2.

Fig. 5 is a sectional detail on the line 5—5 of Fig. 2.

I have used the reference numeral 10 to designate an apartment door, the inside of which is shown in Fig. 1. The grille is mounted at any desired height in the door, preferably in approximately the location illustrated. It includes a pair of inner and outer frame members 11 and 12 respectively which register with each other and which are secured together in any suitable manner.

While I have shown annular frame members, it is to be understood that the frame members might be rectangular, diamond shape, or of any other conformation desired without departing from the invention. Preferably an opening is cut in the door in accordance with the shape of the frame members, and outwardly presented flanges 13, 14 on the frame members overlie the edge of the opening. Screws 15 pass through the flange 13 of the member 11, and entering threaded pockets 16 in the flange 14 of the member 12 afford one convenient type of securing device. It is to be noted that the outer ends of these screws are concealed, so that an intruder cannot detach the outer frame member by loosening the screw.

Frame member 12 is preferably barred as indicated at 17, the bars or grating being, if desired, integrally cast with the member 12. These bars effectively prevent an intruder from inserting his hand through the grille opening to open the door from the inside.

The grille is normally closed by a swinging closure member 18 of the same shape as the frame members 11, 12. Ears 19 integral with the closure member receives a sliding bolt 23 normally urged outwardly by a spring 24 pocketed in the inner end of the sleeve. Movement of the bolt is eliminated by the travel of the shank 25 of a handle 26 in a slot 27 in the sleeve. A keeper 28 rigid with the frame member 11 coacts with the end of the bolt 23. This bolt end is preferably provided with a camming face 29, so that the bolt latches automatically as the closure is swung to.

The central portion of the closure plate 18 is offset to fit within the ring 13, and the edges of the plate lie snugly and flatly against the inner face of this ring, whereby a substantially draft-proof and jimmy-proof closure is provided without the neces-

sity of expensive grooving operations on the door itself.

From the foregoing description it will be apparent that I have provided a grille well suited for the particular requirements of household use outlined above.

Various changes and alterations might be made in the general form and arrangement of parts described without departing from the invention. Hence I do not wish to limit myself to the details set forth, but shall consider myself at liberty to make such changes and alterations as fairly fall within the spirit and scope of the appended claim.

15 I claim:

A door grille for fireproof doors, the grille being of the character which provides a speaking opening and a sight opening, but which prevents the insertion of a hand from the outside of the door, said grille including an outer cross-barred frame member and an inner closure carrying frame member, said

frame members each including portions to be received in a prepared opening in the door and portions to overlie the inner and outer faces of the door, securing devices connecting said frame members together and to the door, the closure comprising a substantially solid metal plate hinged at one edge to the inner frame member, coacting latching means carried by the free edge of the closure plate and the inner frame member respectively, the closure plate including an offset center portion entering the inner frame member when the closure is shut, the closure radially beyond said offset portion providing a flange lying snugly against the inner face of the inner frame member to provide a substantially draft-proof construction and the offset center portion serving as a guard means to prevent the insertion of a jimmying tool under said flange from the outside of the door.

GEORGE W. ACKERMAN.

CERTIFICATE OF CORRECTION.

Patent No. 1,706,835.

Granted March 26, 1929, to

GEORGE W. ACKERMAN.

It is hereby certified that error appears in the printed specification of the above numbered patent requiring correction as follows: Page 1, line 94, after the word "member" insert:

"18 are spaced apart and extend laterally beyond said member, being snugly received between spaced parallel ears 20 integral with the ring 13. A hinge pin 21 is passed through the four aligned ears, thereby hingedly connecting the closure plate to the inner ring 13. The relatively wide flat bearing surfaces defined by the spaced pairs of interfitting ears 19, 20 obviate any danger of the closure plate sagging on its hinges and not swinging true to snugly closed position. The exposed and readily accessible portion of the hinge pin 21 between the ears 19 offers a convenient place of attachment for a coiled tensional spring (not shown) if automatic closing is desired.";

and that the said Letters Patent should be read with these corrections therein that the same may conform to the record of the case in the Patent Office.

Signed and sealed this 23rd day of April, A. D. 1929.

M. J. Moore,
Acting Commissioner of Patents.
